UNITED STATES PATENT OFFICE.

RICHARD T. NEWTON, OF NUTLEY, NEW JERSEY.

SHOCK-ELIMINATOR.

1,329,993.

Specification of Letters Patent.

Patented Feb. 3, 1920.

Application filed July 12, 1915. Serial No. 39,428.

To all whom it may concern:

Be it known that I, RICHARD T. NEWTON, a citizen of the United States of America, residing in Nutley, in the county of Essex 5 and State of New Jersey, have invented certain new and useful Improvements in Shock-Eliminators, of which the following is a specification.

My invention relates to shock eliminators 10 and particularly to a device for use on automobiles or the like the object of my invention being to provide a device of this type improved in certain details of construction shown in the accompanying drawing, in 15 which—

Figure 1 is a vertical section through a shock eliminator in which my invention is embodied in one form; and

Fig. 2 is a cross-section on the line 2—2, 20 Fig. 1.

Only a single shock eliminator unit is shown in the accompanying drawing, although two pair are used in a complete installation, one unit being mounted on each 25 side in the front and rear of the chassis. The unit shown is adapted for use at the front end of the chassis. At the end of the longitudinal member 5 of the chassis frame, is secured, in any suitable manner, a bracket 30 6 rigidly fastened to a tubular casing 7. The semi-elliptic leaf spring 8, on which the chassis is ordinarily directly supported, is jointed to a rocking lever 10 pivoted, on the axis 11, to a boss 12 at the lower end of the 35 tubular casing 7. At the rear of the chassis, the connection between the spring 8 and lever 10 is preferably established through a link 9 as indicated in dotted lines in Fig. 1. Pivoted at 13 on the rocking lever 10 is a 40 connecting rod 14 secured at its upper end 15 to a bearing ring 16 within the casing 7. A heavy coil spring 17 rests at its lower end against the ring 16 and its upper end against an annular abutment 18 formed on the inner 45 wall of a cap 19, which has a sliding fit with the open top of the casing 7. The cap is centrally apertured to receive the internally threaded nut, here in the shape of a thimble 20 provided with a flange 21 overlying and 50 engaging the top of the cap. A connecting rod 22 screwed at its upper end into the thimble 20 extends downward within the casing and is jointed at its lower end to an arm 23 of the buffer lever 24 pivoted on the 55 axis 11 and carrying at its outer end the buffer 25 which may be of any desired con-

struction. For the unit at rear of the chassis, the buffer 25 and its supporting arm 24 are of course omitted. A boss 26 on the upper side of the lever arm 23 bears against the base 27 of the casing 7 in the normal position of the buffer 25. The cap 19 is thus held through boss 26, lever arm 23, connecting rod 22 and thimble 20 in normally rigid relationship to the tubular casing 7. When the car passes over a roughness in the road, the upward pressure of spring 8 upon the bearing ring 16 is accentuated and the shock 60 eliminator spring 17 further compressed momentarily, thus cushioning the shock 65 which would otherwise be transmitted directly to the chassis 5.

Below the bearing ring 16 is arranged a somewhat lighter spring 28, the upper end of which bears against this ring while the 70 lower end rests upon an annular flange 29 in the lower portion of the casing 7. This spring acts in opposite direction to the 75 heavier spring 17 and serves to cushion the upward throw of the body of the car when a deep rut or bump is encountered. In such 80 case the heavy thrust of the springs 8 and 17 strongly tends to throw the chassis upward, with the result that unless counteracted there would be uncomfortably great motion 85 in the car body. As the car rises under the thrust of the springs however, its upward inertia is greater than the movement of the 90 wheels and springs 8, with the consequence that the casing 7 rises faster than the abutment ring 16 and thus compresses the spring 28 between the flange 29 and the ring 16. The violent upward movement of the chassis 95 is thus restrained and an easy riding motion secured.

When the buffer 25 strikes an obstruction, the bell crank lever 24 swings up on the axis 11, pulling down the lever arm 23 and thus, through the connecting rod 22 and thimble 20, sliding the cap down on the 100 tubular casing 7. The spring 17 yields on this downward movement of the cap and cushions the shock to the buffer. Should the shock be sufficiently heavy, the bearing 105 ring 16 is forced downward and the thrust compensated in part by the light spring 28 and the vehicle spring 8 to which the effort is transmitted by the rod 14 and rock lever 10, and, at the rear of the car, by link 9.

It is obvious that the initial tension of 110 the heavy spring 17 may be adjusted to insure its proper action by the extent to which

the thimble 20 is screwed down upon the threaded upper end of the connecting rod 22. By providing the thimble 20 with a rectangular head this adjustment may be 5 made after the device has been mounted upon the car without in any manner disturbing the installation.

Various modifications of the construction 10 will readily suggest themselves to those skilled in the art without departing from what I claim as my invention.

I claim as my invention:—

1. In a shock eliminator for vehicles, a 15 casing rigid with the vehicle frame, a cap slidable upon the upper end of said casing, a rocking lever operatively connected at one end to said casing and at the other end to the vehicle spring, a spring abutment within said casing and moving with said lever, 20 a shock eliminator spring confined between said cap and spring abutment and means for maintaining said cap in normally stationary position with relation to the casing.

2. In a shock eliminator for vehicles, a 25 casing rigid with the vehicle frame, a cap slidable upon the upper end of said casing, a rocking lever operatively connected at one end to said casing and at the other end to the vehicle spring, a spring abutment within 30 said casing and moving with said lever, a shock eliminator spring confined between said cap and spring abutment and means for maintaining said cap in normally stationary position with relation to the casing, together 35 with means for adjusting the normal position of said cap with relation to the casing to vary the initial tension of said spring.

3. In a shock eliminator for vehicles, a 40 casing rigid with the vehicle frame, a cap slidable upon the upper end of said casing, a rocking lever operatively connected at one end to said casing and at the other end to the vehicle spring, a spring abutment within 45 said casing and moving with said lever, a shock eliminator spring confined between said cap and spring abutment, a buffer and an operative connection between the latter and the cap for pulling said cap down on the casing on shock to said buffer.

50 4. In a shock eliminator for vehicles, a casing rigid with the vehicle frame, a cap slidable upon the upper end of said casing, a rocking lever operatively connected at one end to said casing and at the other end to the vehicle spring, a spring abutment within 55 said casing and moving with said lever, a shock eliminator spring confined between said cap and spring abutment, a buffer and an operative connection between the latter 60 and the cap for pulling said cap down on the casing on shock to said buffer, together with a light spring confined below said spring abutment and subjected to compression by the latter through the heavy eliminator 65 spring on shock to the buffer.

5. In a shock eliminator for vehicles, a casing rigid with the vehicle frame, a cap slidable on the casing, a spring confined within the casing and bearing at one end 70 against said cap, a buffer, and an operative connection between said buffer and cap for displacing the latter on shock to the buffer.

6. In a shock eliminator for vehicles, a casing rigid with the vehicle frame, an apertured cap slidable on said casing, an 75 internally threaded nut fitting in said cap aperture and bearing on the cap, a screw rod threaded into said thimble, a lever and an operative connection between said rod and lever, together with a cushioning spring 80 bearing at one end against said cap.

7. In a shock eliminator for vehicles, a casing rigid with the vehicle frame, a cap 85 slidably mounted thereon, a cushioning spring within the casing and bearing at one end against the cap, a lever, and an adjustable connection between the latter and the cap by which the initial tension of the cushioning spring may be determined.

8. In a shock eliminator for vehicles, a 90 casing rigid with the vehicle frame, a cap slidably mounted thereon, a cushioning spring within the casing and bearing at one end against the cap, a lever, and a screwed connection between said lever and cap by 95 which the initial tension of the cushioning spring may be determined.

9. In a shock eliminator for vehicles, a 100 casing rigid with the vehicle frame, a cap slidable on said casing, spring abutments 105 on said cap and casing, a plurality of springs within said casing bearing at their opposite ends against said abutments, a movable abutment between said springs, and an operative connection between said movable 110 abutment and the vehicle spring together with a buffer, a bell crank lever one arm of which supports the buffer and an operative connection between the other arm of said bell crank lever and the casing cap, 115 for the purpose described.

10. In a shock eliminator for vehicles, a 120 casing rigid with the vehicle frame, a cap slidable on said casing, spring abutments on said cap and casing, a plurality of springs within said casing bearing at their opposite ends against said abutments, a movable abutment between said springs, and an operative connection between said movable abutment and the vehicle spring, together with a buffer and an operative connection between the same and the casing cap.

In testimony whereof I have signed my name to this specification, in the presence of two subscribing witnesses.
